Inventor

R.E. Ellerbeck

United States Patent Office.

ROBERT E. ELLERBECK, OF WASHINGTON, DISTRICT OF COLUMBIA.

Letters Patent No. 61,409, dated January 22, 1867.

IMPROVED SKATE.

The Schedule referred to in these Letters Patent and making part of the same.

TO ALL WHOM IT MAY CONCERN:

Be it known that I, ROBERT E. ELLERBECK, of Washington, in the county of Washington, and District of Columbia, have invented certain new and useful improvements in Skates; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in so constructing the attachment of a skate as to fasten it securely to the foot, and at the same time dispense entirely with the use of straps.

Figure 1 is a top plan view.

Figure 2, a side elevation.

Figure 3, a rear end view.

Figure 4 is a transverse vertical section, taken on the line $x x$ of fig. 1.

Figures 5, 6, 7, and 8 are views of portions shown in detail.

A represents the blade of my skate, which is made in the usual manner. To the front portion of the blade is secured a plate, B, for the front portion of the foot to rest on. Another plate, C, is attached for the heel to rest on; these plates being made with a lug or shank, b, which projects downward from their under side and straddle the blade A, to which they are fastened by screws or rivets, as shown in figs. 2, 3, and 4. To the front plate B, a clip, a, shown in plan in fig. 8, is attached by a screw passing through a slot therein, and being screwed into the under side of the plate B, the outer end of the clip a being turned up and made to incline slightly inward, to clasp the sole of the boot or shoe, their inner faces, where they come in contact with the edge of the sole, being roughened, to give them a firm hold on the sole and prevent slipping or becoming loosened. These clips a are not placed directly opposite to each other, but are placed as shown in fig. 1, one being considerably in advance of the other, the object of which arrangement will be hereinafter stated. At the front edge of the heel plate C is secured a raised piece, o, which extends entirely across the plate transversely. In the rear face of this piece o, above the plate C, is formed a dove-tailed groove, as shown in fig. 2, and as represented by m, of fig. 3. This piece o is curved, as shown in fig. 1, it forming the segment of a circle, having its centre at the centre of the front plate B. On the front face of the heel of the boot or shoe is secured a small metal plate, n, shown, with its screws for attaching it, in fig. 5. On the front of this plate, at its lower edge, is a projecting lip, t, formed to fit accurately in the groove in the rear face of the projection o, on plate C. The piece o has a hole in it, through which projects the point of a catch, e, attached to a spring, f, which is secured to the lug b of plate C, as shown in fig. 2, the spring and catch being also shown in fig. 3. The skate is applied to the foot in the position indicated by the blue lines on fig. 1, the clips a being first adjusted to suit the width of the sole, and the skate is then swung around at the heel until it is brought straight under the foot. By thus swinging the heel around, the clips a are made to clasp tightly on the sole, and the plate n, attached to the heel of the boot at the same time, slides into the groove in the piece o, where it is securely held from moving side-wise by the catch e entering a notch or hole in the lip t of the plate n. By these simple means the skate is rigidly and securely fastened to the foot. If desired, the clips a may be arranged to move diagonally on the plate B, as indicated by the dotted lines in fig. 1, and secured from turning by being fitted in grooves or otherwise, by which means they will be less likely to spread in use. Instead of the dove-tailed groove in the projection o, the groove may be made as shown in figs. 6 and 7, the plate n being formed to correspond therewith. The spring f may also be attached to the under side of plate C, with its catch e fitting up through a hole therein, to engage in a similar hole or notch in plate n, as shown in fig. 7. By these means I construct a skate that dispenses entirely with the use of straps, leaving the muscles and veins of the foot free to act without obstruction. Skates thus constructed can be attached or detached in an instant, it only being necessary to press down the spring f, and push the heel to one side until the plate n is disengaged from the piece.

Having thus described my invention, what I claim, is—

1. The laterally adjustable clips a, attached to the skate, on a line diagonal to the longitudinal plane of

the blade A, for the purpose of grasping and securely holding the boot or shoe when applied thereto, substantially as shown and described.

2. The projection o, having a groove formed therein, and arranged to operate in connection with the plate n, and secured by the catch e or its equivalent, substantially as set forth.

3. In combination with the clips a, arranged as described, I claim the grooved projection o, and plate n, spring f, and catch e, arranged to operate as and for the purpose set forth.

RBT. E. ELLERBECK.
